(57) **CLAIM**

The ornamental design for a flip lid bin, as shown and described.

DESCRIPTION

FIG. 1 is a top perspective view of a flip lid bin; FIG. 2 is a bottom perspective view of the flip bin lid shown in FIG. 1;

FIG. 3 is a top plan view thereof;

FIG. 4 is a bottom plan view thereof;

FIG. 5 is a front elevational view thereof; and,

FIG. 6 is a left side elevational view thereof.

The broken lines shown in the drawings are for the purpose of illustrating part of the flip lid bin and form no part of the claimed design. A rear elevational view of the flip lid bin is not shown because it is a mirror image of the front elevational view of the flip lid bin that is shown in FIG. 5. A right side elevational view of the flip lid bin is not shown because it is a mirror image of the left side elevational view of the flip lid bin that is shown in FIG. 6.
